TUMBLER HOLDING TRAY

Charles H. Rennels, Woodworth, Ohio

Application July 22, 1957, Serial No. 47,040

Term of patent 14 years

(Cl. D44—10)

I claim:

The ornamental design for a tumbler holding tray, as shown.
